OLAV JACOBSEN, STEVEN TROY, AND HALFDAN KJELDSEN, OF VANCOUVER, BRITISH COLUMBIA, CANADA.

ROOF-ASPHALTING MACHINE.

1,121,728.

Specification of Letters Patent. Patented Dec. 22, 1914.

Application filed September 4, 1913. Serial No. 788,064.

To all whom it may concern:

Be it known that we, OLAV JACOBSEN, STEVEN TROY, and HALFDAN KJELDSEN, citizen of the Dominion of Canada, subject of the Emperor of Austria-Hungary, and subject of the King of Norway, respectively, residing at Vancouver, in the Province of British Columbia, Canada, have invented certain new and useful Improvements in 10 Roof-Asphalting Machines, of which the following is a specification.

This invention relates to a machine for applying to paper or other fabric a water-proofing material, such as asphaltum, and is 15 designed to enable this operation to be performed on the roof of a building whereby the asphaltum impregnated paper may be applied direct to the roof while it is hot and in a favorable condition for such application.

In the usual practice of roofing with such material, tarred paper is applied to the roof and is mopped with hot asphaltum as each 20 layer is laid. This process is troublesome and is unsatisfactory, in that paper which 25 has been treated with a water-proofing material and allowed to cool, does not lie evenly; and further in applying subsequent 30 layers of paper the intervening asphaltum material cannot be evenly spread by hand.

In the device, which is the subject of this application, the roll of paper, a tank of heated asphaltum, and the necessary rollers for passing the paper through the asphaltum and for smoothing over the surface of the paper the asphaltum taken up by it, are all mounted within a suitable frame on 35 wheels, to which wheels a driving mechanism is applied by which the machine may 40 be laterally traversed over a roof a measured distance such as will give the required overlap between each layer. The whole device is compactly arranged that it may be 45 run close up to the party or fire wall of the building and the paper as cut off at the rolls will reach to the party wall and afford a "flashing" up it.

The invention is particularly described in the following specification, reference being 50 made to the drawings by which it is accompanied, in which:

Figure 1 is a vertical longitudinal section of the machine taken in a plane at right angles to the line of travel of the machine,

Fig. 2 is an enlarged detail perspective view 55 of a portion of the mechanism. Fig. 3 is an enlarged detail perspective view of another portion of the invention. Fig. 4 is an end elevation looking from left to right in Fig. 1. Figs. 5 and 6 are detail perspective views 60 of one of the rollers.

In these drawings 2 represents a suitable frame which is mounted on wheels 3 secured on axles 4. Removably supported within this frame 2 is a deep sheet metal asphaltum 65 holding trough 5, which in cross section is rounded at the bottom and flared forward to the open top. Into this trough 5 the hot asphaltum is poured, and if found necessary, may be maintained at the required heat by 70 artificial means such as by a hydrocarbon flame or an electric resistance coil. Within our present practice this provision has not been found necessary. A roller 6 of small diameter is supported in the bottom of this 75 trough in bearings in the lower end of handle rods 7, the lower ends of which rods project beyond the bearing of the roller to such distance as will enable them to support the roller clear of the bottom of the trough. 80 The bearing ends of the handle rods 7 move in vertical guides 8 so that the roller is supported in the tank so that it will not touch the sides, and the upper ends of the rods 7 are formed as handles by which the roller 85 may be lifted up the guides 8 and from the trough, when required.

Mounted in open bearings on standards 11 secured on the upper sides of the frame 2 opposite to the trough is a roll of paper 10. 90 Between this paper roll and the top of the trough two hollow feed rollers 12 and 13 are mounted in bearing blocks 14 which are freely movable in guide standards 15 secured to each side of the frame, the standards being angled from the paper roll, so that the paper 16 delivered from the upper side of the roll 10 may pass over the outer side of the upper roller 12, under the roller 6 in the trough and over the lower roller 13 95 without interfering. The rollers 12 and 13 are maintained hot by hot sand filled into them through an aperture 36 in the end of each, the maintenance of heat being necessary to prevent the asphaltum accumulating 100 on the surfaces of the rollers. The upper roller rests upon the surface of the lower roller and its weight is supplemented to

hold it in such contact by a weighted lever 18 pivotally connected at 19 to one side of each bearing standard and connected by a rod 20 to the upper bearing block 14. A recess 21 is turned in the surface of the upper roller 12 about its midlength, the object of which recess is that a thicker layer of asphaltum shall be left along the mid-width of the paper where the edge of the next 16 overlapping strip of paper is to be applied.

The rollers 12 and 13 are driven by intermeshing gear wheels 22, 23 and by a crank handle 24 on the axle of the paper roller and a light frictional check or brake 15 37 is applied to the upper roll to prevent the paper overrunning the feed rollers. The axles 4 of the wheels are mounted in bearing forks 25, the stems 26 of which are threaded and provided with upper and lower nuts between 20 which the fork is secured to the frame and by which the vertical distance of the wheels from the frame may be adjusted.

On the outwardly projecting end of the axles 4 of one of the wheels 3, is secured a gear wheel 27 in the teeth of which mesh 25 those of another wheel 28, the axle 29 of which is mounted in bearings in a bracket 30 secured to the frame 2 and in the teeth of this wheel 28 engages a pawl 32 pivotally 30 connected to a handle lever 33 which is loosely mounted on the axle 29 on which the wheel 28 is secured. These gear wheels 27, 28 are so proportioned to the supporting wheels 3 that the movement of the handle 35 lever 33 within operative limits will rotate the driving wheel 3 through a distance sufficient to traverse the machine the width of the weather exposure of the paper.

Every precaution is taken to make the 40 machine as light as possible fitting it for conveyance to and for use on the roof of a building. The height of the contact of the rollers 12 and 13 from the roof level and the distance of these rollers from the side 45 of the machine to which the paper is delivered are such that when the paper is cut off close to the rollers a length of paper is left sufficient to reach over the space occupied by the machine and to the party wall 50 and will leave about six inches of "flashing" up that wall.

In use, the machine is placed to move 55 along the roof as close as practicable and parallel to one party wall 35, and the paper 16 is taken from the upper side of the roll 10, which is toward that party wall, is passed over the same side of the upper roller 12, and around the roller 6 which is immersed in the hot asphaltum within the 60 trough 5. Thereafter the paper passes between the rollers 12 and 13 where any undesired surplus of the asphaltum is removed from the paper. Rotation of the rollers 12 and 13 feeds the paper through as described 65 and delivers it from the side of the machine

farther from the wall 35, and as delivered it is carried by tongs to the other end of the roof and applied with a "flashing" to the party wall at that end. When the length of paper which has passed from the machine 70 has been laid evenly on the roof up to the machine the paper is cut adjacent to the rollers 12-13 and the length reaching from the roof to the rollers is just sufficient to lay on the space occupied by the machine and to extend as a "flashing" up the party wall 35.

Having now particularly described our invention we hereby declare that what we claim as new and desire to be protected in 80 by Letters Patent, is:

1. A roof asphalting machine, comprising the combination with a suitable frame which is mounted on wheels, of mechanism connected to said wheels by which the machine 85 frame may be moved laterally with respect to the length of the paper, of an asphaltum trough removably supported within the frame, bearings projecting from the upper sides of the frame in which a roll of paper 90 may be carried, feed rollers rotatably mounted in bearing blocks which are supported in guide ways secured to each side of the frame to support the rollers over the trough, means for simultaneously rotating 95 said rollers and a roller rotatably supported in the bottom of the trough.

2. A roof asphalting machine, comprising the combination with a suitable frame which is mounted on wheels, of mechanism connected to said wheels whereby the machine may be moved laterally with respect to the length of the paper over uniform distances, an asphaltum trough removably supported within the frame, supporting standards on 100 each side of the machine frame adapted to carry a roll of paper, feed rollers rotatably mounted in bearing blocks which blocks are supported in guide ways secured to and projecting upward from each side of the frame 110 one of which feed rollers has a circumferential recess extending throughout its middle portion, means for simultaneously driving said feed rollers and a roller rotatably supported in the bottom of the trough. 115

3. A roof asphalting machine, comprising the combination with a suitable frame which is mounted on wheels, of mechanism connected to said wheels whereby the machine may be moved laterally with respect to the 120 length of the paper, an asphaltum trough removably supported within the frame, a paper carrying roll rotatably mounted on standards projecting from the sides of the machine at the opposite end to the trough, hollow rollers rotatably mounted in contact with one another between the paper carrying roll and the trough, means for simultaneously driving said rollers, provision for heating said rollers and a roller rotatably 125 130 135

mounted in the bottom of the trough on the ends of handle bars which are vertically movable in guides in the ends of the trough.

4. A roof asphalting machine, comprising the combination with a suitable frame having a paper carrying roll rotatably mounted at one end, an asphaltum trough at the other end, a roller rotatably mounted in the bottom of the asphaltum trough, feed rollers 10 rotatably mounted between the paper carrying roll and the asphaltum roll the upper of said rollers in contact with the lower through a short distance at each end and circumferentially recessed about the midlength, and means for simultaneously driving said rollers.

5. A roof asphalting machine, comprising the combination with a suitable frame, of a rotatably mounted paper carrying roll, an asphaltum trough, a roller rotatably mounted in the asphaltum trough, feed rollers rotatably mounted between the paper carrying roll and the asphaltum trough one side of the upper roller projecting over the same 25 side of the lower roller and circumferentially recessed about its midlength, and means for simultaneously rotating said rollers.

6. A roof asphalting machine, comprising the combination with a suitable frame mounted on wheels which have a lateral traversing mechanism, a paper carrying roll rotatably mounted on one end of the machine, an asphaltum trough at the other end 30 of the machine, a roller rotatable in the bottom of the asphaltum trough, feed rollers rotatably mounted in contact with one another between the paper carrying roll and the asphaltum trough one for receiving the 35 paper from the roll, delivering the paper to the roller in the asphaltum trough and the other for receiving it therefrom and delivering the paper from the machine, the distance from the floor level on the delivery 40 side of the machine to the delivery of the paper from the feed rollers being greater than the distance from the same place on the floor level to the opposite end of the machine.

7. In a roof asphalting machine, a wheeled frame, a paper carrying roll mounted with its axis held transversely to the axes of the wheels of the frame, a coating tank, feeding rollers for feeding the paper up and 50 down in the coating tank, a guide roller in the coating tank around which the

paper passes; the axes of said feeding and guide rollers lying in the direction of movement of said frame, said feeding rollers including means for forming a longitudinal thickened coating on the paper intermediate of the ends thereof, and mechanism for driving said frame laterally a distance sufficient to lay the paper so as to lap the unthickened portions of adjacent strips. 60

8. In a roof asphalting machine, a wheeled frame, a paper carrying roll mounted with its axis held transversely to the axes of the wheels of the frame, a coating tank, feeding rollers for feeding the paper up and 70 down in the coating tank, a guide roller in the coating tank around which the paper passes; the axes of said feeding and guide rollers lying in the direction of movement of said frame, said feeding rollers including 75 means for forming a longitudinal thickened coating on the paper intermediate at the ends thereof, and mechanism for driving said frame laterally a distance sufficient to lay the paper so as to lap the unthickened 80 portions of adjacent strips, and means for heating said feeding rollers to prevent sticking of the coated paper.

9. A roof asphalting machine, which comprises a frame, supporting wheels for 85 conveying the frame transversely, a paper carrying roll transversely mounted on said frame, a coating tank mounted on said frame, feed rollers for feeding the paper up and down in the coating tank and a guide 90 roller in the coating tank around which the paper passes, the axes of said feeding and guiding rollers lying parallel to that of the paper carrying roll and in the direction of movement of said frame, means for moving 95 said frame, said frame having vertical guideways, bearing members longitudinally movable in said guideways for carrying said guide roller, said bearing members including upwardly projecting angle extensions 100 having handle eyes whereby said guide roller may be bodily removed with its bearings from said tank, substantially as shown and described.

In testimony whereof we affix our signatures in presence of two witnesses.
